[57] ABSTRACT

A digital frequency multiplication system for generat-

ing a pulse rate or frequency F_v which is a function of a desired machine velocity, and then deriving the component frequencies representative of the machine velocity along at least two orthogonal reference axes.

Linear interpolation control along the orthogonal axes is provided using digital differential analyzers having numerator shift registers receiving coded intelligence representative of displacement along these axes, and denominator shift registers for receiving coded intelligence representing the root of the sum of the square of the respective displacements along the reference axes.

Circular interpolation is provided along the reference orthogonal axes using digital differential analyzers having numerator shift registers which are a function of the displacement along the other axes, and denominator shift registers for receiving intelligence which is a function of the root of the sum of the squares of the displacements along the axes. The output of the digital differential analyzer is fed back to modify the numerator of the other digital differential analyzer as circular interpolation proceeds.

The ratio of N/D is less than unity. When violation of this relationship is impending, the coded intelligence of the larger of the displacements along a reference orthogonal axis is then entered into the D shift registers.

Manual override by an operator and for scaling of the weighted value of the output pulse train F_v provides further flexibility for the system.

**PROGRAMMABLE DIGITAL FREQUENCY
MULTIPLICATION SYSTEM WITH MANUAL
OVERRIDE**

BACKGROUND OF THE INVENTION

1. Field Of The Invention

This invention relates to the numerical control of machine tools and in particular to a digital frequency multiplication system.

2. Discussion Of The Prior Art

The classic digital differential analyzer (DDA) is described in "Arithmetic Operations In Digital Computers" by R.K Richards, pp 303-305, Van Nostrand Co., Inc. 1955. An improved DDA is described and claimed in U.S. Pat. No. 3,740,535 entitle "Numerical Contouring Control System" invented by Andras Szabo. This invention utilizes as one component the modified DDA of U.S. Pat. No. 3,740,535.

In describing the DDA, conventional nomenclature refers to one shift register as the integrand and the other shift register as the remainder. In this description, the magnitude of the integrand will be referred to as the numerator N and the capacity of the remainder register as the denominator D. Further, the term digital frequency multiplier will frequently be used as well as the term digital differential analyzer because in the main our interest is in digital frequency or pulse rate multiplication. (It should be recognized, of course, that the DDA is a frequency multiplier.)

Improved techniques for numerical controls now permit programming the desired machine path velocity in direct speed dimensions. Once that velocity has been determined (this velocity path will be identified as the velocity vector F_v) it is converted into orthogonal component velocities for control purposes. U.S. Pat. No. 3,428,876 to Kelling describes a technique for so converting the commanded vector velocity; this technique will be discussed vis-a-vis the teachings of the instant invention.

SUMMARY OF THE INVENTION

A frequency multiplication system is disclosed having a first digital differential analyzer including a numerator shift register N and a denominator shift register D. Means are arranged for applying a constant frequency pulse train f_c to the first digital differential analyzer. Means supply a maximum coded input in the form of linear measure per unit time to the N shift register. Additional means apply a programmable input D to the D shift register which is a function of said maximum coded input to provide for scale of one to one weighted vector output velocity F_v in accordance with:

$$F_v = f_c \times N/D$$

Additional means are provided to provide a new denominator $2D_1, 4D_1$ to provide a new weighted value of the output F_v .

Additionally, means are provided for selecting a percentage of the maximum coded input to provide manual override.

Additionally, the system is adapted for linear interpolation along at least two orthogonal axes by providing at least second and third differential analyzers each having N_2N_3 and D_2D_3 shift registers, respectively. The pulse output F_v is applied to the second and third differential analyzers. Means apply the programmed displacement along one orthogonal axis to the N_2 shift reg-

ister. Similarly, means apply the programmed displacement along the other orthogonal axis to the N_3 shift register. Means are arranged for applying the square root of the sum of the squares of said programmed displacements RSS to the D_2D_3 shift registers whereby the outputs of the digital differential analyzers are:

$$F_{\text{along one orthogonal axis}} = f_v \times N_2/D_2$$

and

$$F_{\text{along the other orthogonal axis}} = f_v \times N_3/D_3.$$

- 10 Circular interpolation along at least two orthogonal axes (x, y) is also provided. At least second and third differential analyzers are provided having N_2N_3 and D_2D_3 shift registers, respectively. The output pulse train F_v is again applied to the second and third differential analyzers. Means apply the programmed displacement along the y orthogonal axis to the N_2 shift register. Means apply the programmed displacement along the x orthogonal axis to the N_3 shift register. Means are arranged for supplying the square root of the sum of the squares $\sqrt{\Delta x^2 + \Delta y^2}$ (RSS) to the D_2 and D_3 shift registers whereby the outputs of the digital differential analyzers are:

$$F_x = \Delta y / RSS \times F_v;$$

$$F_y = \Delta x / RSS \times F_v.$$

- 25 Means couple back F_x and F_y to the N_3 and N_2 registers respectively, to modify the magnitude of the respective numerators N_2 and N_3 as circular interpolation progresses. Means are coupled to the shift registers D_2 and D_3 for comparing Δx and Δy with RSS, for changing the 30 magnitude of RSS, i.e. the D_2 and D_3 shift registers whenever

$$\Delta x \geq RSS$$

or

$$\Delta y \geq RSS.$$

FIG. 11 is a prior art technique for generating the orthogonal component axial velocities for a vector velocity F_v .

GENERAL DESCRIPTION

Improved programming techniques for numerical controls now permit programming the desired machine path velocity in direct speed dimensions. For example, an F character followed by five digits may be used to set the machine speed from 000.01 to 999.99 inches per minute (IPM). The F value is modal, meaning that it is used until a new number is programmed. Previous methods required programming a number inversely proportional to the time required, a new number usually being required for every new motion command. In most control systems a feed rate override (FRO) is provided so that the machine operator can manually override the programmed speed command by selecting what percentage of the programmed speed will be utilized. The override selection varies usually from zero to one hundred and twenty percent with control being either continuous or in discrete steps throughout the interval.

In general, the programmed and manually selected parameters are used to generate a digital pulse rate or frequency which represents the desired velocity. This frequency will be called the vector frequency F_v . Typically each F_v pulse represents one increment usually 0.0001 inch of vector or machine path motion. Further processing of the F_v pulses provides the frequencies F_x and F_y to control the respective velocities along the orthogonal axes x and y (motion along the z axis may also be controlled in three dimension situations, but in the interests of simplicity, this discussion will be confined to the $x-y$ plane).

DESCRIPTION OF THE PREFERRED EMBODIMENT

Conventional techniques used for generating F_v employ either a voltage controlled oscillator (VCO) followed by a digital differential analyzer DDA as shown in FIG. 9 or two cascaded DDA as shown in FIG. 10. The frequency at the input to the final DDA determines the overall time resolution capability for the F_v generator. A higher frequency input to the final DDA results in more accurate location of the F_v pulses along the time axes. However, when the feed rate override is used to reduce the programmed speed, the instantaneous frequency error of F_v will become larger. Further, in the FIG. 9 arrangement, thermal instabilities of the VCO creates errors in the generation of F_v .

Referring now to FIG. 1, a program source 10 provides coded information which is transmitted to the program storage 12. The programmed value of the desired feed rate (IPMP) is supplied as the numerator N to the digital frequency multiplier 14.

The operator selects the override percentage which is transmitted to the encoding logic 16; this logic selects an address in the read only memory (ROM) 18 which then provides the proper denominator D_1 value. The D_1 number is applied to a binary multiplier 20 where it may be scaled before being supplied to the DFM 14. The DFM multiplies the constant frequency pulse train f_c to provide F_v :

$$f_c \times N/D = F_v$$

In one practical application of this invention a five decimal digit format is used for the programmed feed rate in order to permit programming from 00000 to 99999 to represent the desired speeds of 000.00 to 999.99 inches per minute (IPM) at a resolution of 0.01 IPM.

The programmed data is converted to a binary number and stored in the N register.

The digital storage elements are 25 bit serial binary shift registers operating at 500 kilobits per second data rates. The maximum iteration or cycle rate is 20,000 cycles per second.

The clock pulses f_c and 20,000 pulses per second. If an F_v pulse represents 0.0001 inches of vector motion, an F_v of 20,000 pulses per second will represent 120 IPM. In order to achieve speeds greater than 120 IPM, without modifying the basic data bit rate, the D value is scaled, that is, it is multiplied by a binary scale factor; 2, 4, etc., and the weight of the F_v pulse is changed accordingly (i.e. to 0.0002 inch, 0.0004 inch, etc. in the subsequent control circuitry). The scale factor that is used is dependent upon the programmed feed rate (IPM) as shown in the table of FIG. 2.

The denominator D_1 is a function the selection feed rate override:

$$D_1 = IPM \max \times (FRO \max / FRO)$$

Where:

D_1 = the denominator value for scale of one operation,

$IPM \max = 10,000$ (the resolution of IPM max is the same as IPMP in the numerator),

$FRO \max = 120$ percent,

FRO = the selected value of feed rate override in 10 percent steps from 10-120 percent.

The table of FIG. 3 lists the denominator values for various selected override rates (for an override of 0 percent, the operation of the DFM is inhibited so that no F_v pulses are produced). As may be seen from a study of FIG. 2, the scale factors 1, 2, 4 cause some multiple of D_1 (the denominator for scale of one operation) to be used as the denominator D in the DFM 16, i.e. D_1 , $2D_1$, $4D_1$, etc.

Additional storage capacity in the read only memory (ROM) can be used to modify the denominator D to accept various formats of input information. For example, the programmed feed rate may be in inches per minute (IPM) or millimeters per minute (MMPM). Additional stored denominator values may be selected to represent inches per revolution (IPR) in which case the input frequency f_c would be derived from a frequency representing the speed of revolution of a spindle, for example. The ROM can also be a source for numerator values for generating various fixed speeds for fast, medium and slow manual jog, or for other manual operational modes, such as incremental jog.

Automatic acceleration control can be provided with the addition of more control circuitry. For example, the N value can be linearly incremented over a period of time, by adding some number to the N register every iteration, until it equals the programmed IPM causing the F_v frequency to increase linearly to the desired value.

Similarly, as the final machine position is approached, the N value can be iteratively decremented by some value to provide automatic deceleration control.

Generally in numerical contouring control systems, the desired machine vector velocity F_v is accomplished by controlling its velocity (frequency) components F_x , F_y along two or more orthogonal axes. In the $x-y$ plane for linear displacement, $F_x = F_v \cos \theta$ and $F_y = F_v \sin \theta$ where θ is the angle between F_v and the y axis.

Similarly, in circular displacement the components F_x and F_y are functions of the sine and cosine. A schematic diagram of the conventional approach to the generation of the component velocities is shown in FIG. 11. This is essentially the approach taken in U.S. Pat. No. 3,428,876. As will be seen, two digital differential analyzers, DDA's are used with a vector feedback approximation (F_v approx) to provide the trigonometric conversion. The x axis and the y axis initial departures, Δx and Δy are described from the control input data. The denominator term of the DDA (DDA MODULO) refers to the capacity of the remainder register of the DDA.

In operation, a pulse from the F_v input is added to the F_v Error Counter enabling the operation of both DDA's to generate pulses at the F_x and F_y outputs. These outputs (F_x , F_y) are then summed using a vector sum approximation algorithm. The generated approximation of the vector frequency (F_v approx) is subtracted at the F_v Error Counter cancelling the input F_v and disabling the DDA's. This process is repeated for each F_v input pulse received. Since the denominator term of the DDA's is fixed, i.e. (DDA MODULO) the ratio of F_x and F_y will be the ratio of the two numerator terms Δx and Δy . Since each pulse at F_x and F_y represents one increment of displacement on the respective axis, accurate linear motion is achieved. However, the accuracy of the rate of change of vector position, i.e. the vector velocity F_v is directly proportional to the accuracy of the vector summing approximation algorithm.

Referring now to FIG. 4, the instant invention teaches the technique for achieving trigonometric frequency multiplication for linear displacement using two digital frequency multipliers DFM's 22 and 24. The numerator terms are Δx and Δy , respectively; however, the denominator is RSS, i.e. the number derived from:

$$RSS = \sqrt{\Delta x^2 + \Delta y^2}$$

i.e. the vector length (RSS is an acronym derived from Root of Sum of Squares). The velocity accuracy is proportional to the accuracy of RSS with respect to the true vector length. The RSS calculation using the given Δx and Δy values need only be done once before the frequency multiplication process starts. This value can be calculated to any desired accuracy using a general numerical processor with a suitable iterative algorithm, thus eliminating the need for the feedback pulse summing algorithm hardware shown in FIG. 11. Since the calculation is performed once for each move programmed, the numerical processor is free to do other tasks while the frequency multiplication is taking place during motion.

In linear path control, the numerator term of both DFM's 22, 24 remain constant throughout the move. The arithmetic algorithm used to calculate the denominator RSS is arranged so that the RSS will always be initially larger than both numerator terms. This insures that the N/D ratio is less than unity.

During circular path control, the numerator N of one DFM (FIG. 5:26) is modified by the output of the other DFM (FIG. 5:28). This is done because one orthogonal increment goes from 0 to a maximum, while the other orthogonal increment goes from a maximum to zero. Stated differently an instantaneous or continuous tangent (i.e. the vector frequency F_v) has no component parallel to the x axis at zero degrees, but gradually builds up

to a maximum at 90°; the converse is true for the component parallel to the y axis.

Although the RSS term which is calculated before motion begins is, initially, larger than both numerator terms, as motion takes place, one of the modified numerator terms may exceed the value of RSS. This could take place in the first quadrant, for example, in the region 0°-16° and 84°-90°. In order to prevent this happening, the approximate sine and cosine relationship of the DFM ratios can be modified to a tangent and unity relationship, while still maintaining the same ratio of F_x to F_y since:

$$\text{sine/cosine} = \text{tangent}/1$$

This is done by comparing the numerator terms N_x , N_y (i.e. Δx , Δy) with the RSS term. When one of the numerator terms N_x or N_y becomes equal to or larger than the RSS value, the larger term is used as the denominator of both DFM's 26, 28.

The logic circuitry of FIG. 6 checks the instantaneous numerator N_x and N_y with the RSS value. This is done by a pair of comparators 30, 32. The output of comparator 30 is applied to NOT gate 34 and to AND gate 36; the output of comparator 32 is applied to NOT gate 38 and AND gate 40. The outputs of the NOT gates 34, 38 are connected to AND gate 44. The output of the AND gates 36, 40, 42 are applied to OR gate 44.

During most of the circular path control N_x and N_y are less than RSS. The outputs of the comparators are 30 a logic ZERO, and hence AND gate 42 is enabled, passing RSS as the denominator value D. Suppose N_x becomes $\geq$ RSS. Comparator 30 would output a logic ONE and AND gate 42 would be disabled; however, this logic ONE would enable AND gate 36 passing N_x to OR gate 44. The magnitude of the denominator D would now be Δx as shown in FIG. 7. Similarly, when $N_y \geq$ RSS.

The mode shown in FIG. 5 is called frequency multiplication for circular interpolation using the sine and cosine algorithm; the mode shown in FIG. 7 is frequency multiplication for circular interpolation using the tangent and unity algorithms. This approach can cause some velocity error, but the error will always be less than that caused by the discrepancy between the calculated RSS value and the true vector length, and the transition from the sine and cosine algorithm to tangent and unity algorithm occurs smoothly with no step change in velocity.

A summary of the numerator and denominator register contents for the F_x axis and F_y axis is shown in the table of FIG. 8. The I and J nomenclature is that adapted by the Electronic Association of Washington, D.C. when programming for circular interpolation. The above description of the trigonometric DFM is based on a machine controlled in one plane, described by the two orthogonal degrees of freedom, but the technique is also applicable for controlling a third axis orthogonal to the other two, by adding another DFM, and modifying the calculation of RSS to include the third dimension.

The trigonometric approach described above provides very accurate vector path control, and vector velocity control accuracy proportional to the degree of accuracy for the RSS calculation. Path accuracy of the DFM is maintained over its full range with an error of less than one increment.

We claim:

1. A frequency multiplication system having a first digital differential analyzer including a numerator shift register N and a denominator shift register D comprising:

means for applying a constant frequency pulse train 5
fc to said first digital differential analyzer;

means for applying a maximum programmed coded input in the form of linear measure per unit time to
said N shift register;

means for applying a programmable input D₁ to said 10
D shift register which is a function of said maximum programmed coded input to said N register to provide for scale of one-to-one weighted vector output velocity F_v, said vector velocity F_v being in accordance with the equation:

15

$$F_v = fc \times N/D.$$

2. A frequency multiplication system according to claim 1 comprising:

means, coupled to said programmable input means 20
for modifying the denominator input D₁ to provide a new denominator 2D₁, 4D₁, etc., which provides variable weighted factors (absolute linear measure per pulse) for said vector output F_v.

3. A frequency multiplication system according to claim 1 comprising:

means, coupled to said maximum programmed coded input, for selecting a variable percentage override 25
of said maximum programmed coded input to said D shift register to provide various magnitudes of D₁ which are a function of said selected variable feed rate override.

4. A frequency multiplication system according to claim 3 comprising:

means, coupled to said programmable input means, 35
for modifying the variable magnitude D₁ to provide new denominators 2D₁, 4D₁ etc., which provides variable weighted factors (absolute linear measure per pulse) to said vector output F_v.

5. A frequency multiplication system according to claim 1 adapted for linear interpolation along at least 40
two orthogonal axes comprising:

at least second and third digital differential analyzers
each having N₂, N₃ and D₂, D₃ shift registers respectively;

means for applying the pulse train output F_v to said 45
second and third digital differential analyzers;

means for applying the programmed displacement along the one orthogonal axis to the numerator shift register N₂ of said second digital differential analyzer;

means for applying the programmed displacement along the other of said orthogonal axes to the nu-

merator shift register N₃ of said third digital differential analyzer; and
means for applying the square root of the sum of the squares of said programmed displacements RSS to the shift registers D₂, D₃ of said second and third digital differential analyzers, whereby the outputs of the second and third digital differential analyzers are respectively:

$$F_{along\ one\ orthogonal\ axis} = F_v \times N_2/D_2$$

$$F_{along\ the\ other\ orthogonal\ axis} = F_v \times N_3/D_3.$$

6. A frequency multiplication system according to claim 1 adapted for circular interpolation along at least two orthogonal axes (x,y) comprising:

at least second and third digital differential analyzers
each having N₂, N₃ and D₂, D₃ shift registers respectively;

means for applying the pulse train output F_v to said second and third digital differential analyzers;

means for applying the programmed displacement Δy along one orthogonal axis to the numerator shift register N₂ of the second digital differential analyzer;

means for applying the programmed displacement Δx along the other of said orthogonal axes to the numerator shift register N₃ of said third digital differential analyzer;

means for applying the square root of the sum of the squares of said programmed displacements (RSS) to the shift registers D₂, D₃ of said second and third digital differential analyzers, whereby the outputs of said second and third differentials F_x and F_y respectively are:

$$F_x = \Delta y / RSS \times F_v;$$

$$F_y = \Delta x / RSS \times F_v;$$

means for coupling back F_x to the numerator register N₃ of said third digital differential analyzer to modify the magnitude of Δx as circular displacement progresses;

means for coupling back F_y to the numerator register N₂ of said second digital differential analyzer to modify the magnitude of Δy as circular displacement progresses.

7. A frequency multiplication system according to claim 6 comprising:

means coupled to said shift register D₂ and D₃ for comparing Δx and Δy with RSS, for changing the magnitude of RSS to either Δx or Δy whenever:

$$\Delta x \geq RSS$$

50 or

$$\Delta y \geq RSS.$$
